CLAIM

We claim the ornamental design for a coffee pod embodying the new design, as shown and described.

DESCRIPTION

FIG. 1 is a perspective view of a coffee pod in accordance with a first embodiment of the new design.

FIG. 2 is a front view of the coffee pod in accordance with the first embodiment of the new design.

FIG. 3 is a first side view of the coffee pod in accordance with the first embodiment of the new design.

FIG. 4 is a second side view of the coffee pod in accordance with the first embodiment of the new design.

FIG. 5 is a third side view of the coffee pod in accordance with the first embodiment of the new design.

FIG. 6 is a bottom view of the coffee pod in accordance with the first embodiment of the new design; and,

FIG. 7 is a top perspective view of the coffee pod in accordance with the first embodiment of the new design. In the drawings, the broken lines depict portions of the article that form no part of the claimed design.
